UNITED STATES PATENT OFFICE

ETTA M. SQUIRES, OF AMITYVILLE, NEW YORK

DESIGN FOR A TOILET CABINET

Application filed May 23, 1930. Serial No. 35,729. Term of patent 14 years.

To all whom it may concern:

Be it known that I, ETTA M. SQUIRES, a citizen of the United States and a resident of Amityville, Long Island, in the county of Suffolk and State of New York, have invented the new, original, and ornamental Design for Toilet Cabinet, of which the following is a specification.

Reference is had to the accompanying drawings, forming part thereof, wherein—

The figure is a front perspective view of a toilet cabinet showing my new design.

I claim—

The ornamental design for a toilet cabinet substantially as shown.

ETTA M. SQUIRES.
